Filed Feb. 22, 1973, Ser. No. 334,627

Term of patent 14 years

Int. Cl. D28—03

U.S. Cl. D86—10 F

FIG. 1 is a perspective view of a hair dryer showing our new design.

FIG. 2 is a right side elevational view of the hair dryer shown in FIG. 1, it being understood that the air inlets omitted for convenience of illustration are continuous in the path indicated by the dot-dash line.

FIG. 3 is a top plan view of the hair dryer shown in FIG. 1.

FIG. 4 is a front elevational view of the hair dryer.

FIG. 5 is a rear elevational view.

The bottom of the hair dryer is substantially flat and unornamented. The left side elevational view of the hair dryer is a mirror image of the right side elevational view shown in FIG. 2.

We claim:

The ornamental design for a hair dryer, as shown and described.
